UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE-POSITIONING MEANS.

Original application filed July 10, 1922, Serial No. 573,801, now Patent No. 1,667,936, dated May 1, 1928.
Divided and this application filed July 9, 1926. Serial No. 121,421.

This invention relates to machines for use in the manufacture of boots and shoes, and more particularly to means for positioning shoes in such machines, this application being a division of a copending application Serial No. 573,801, filed on July 10, 1922 maturing into Patent No. 1,667,936, May 1, 1928. The invention is herein illustrated in its application to a machine of the type shown in the copending application, for lasting the heel ends of tennis shoes, but is not limited to machines of that particular type nor to machines designed for that particular use.

A feature of the invention consists in novel means for locking a movable shoe support in operative relation to means which operates upon the shoe. Machines of the type illustrated comprise heel-lasting mechanism, and a shoe support which is movable rearwardly from a shoe-receiving position into position to present the shoe to the lasting mechanism, this mechanism including a heel band into engagement with which the shoe is carried by the rearward movement of the shoe support for clamping the upper about the heel end of the last. In the prevailing practice in the manufacture of tennis shoes neither the upper nor the insole is fastened to the last prior to the heel end lasting operation, and it is accordingly desirable that after the heel end of the upper has been clamped to the last by the heel band, an opportunity be afforded for the operator to position the insole in proper relation to the last and to the heel end of the upper. The invention accordingly provides means for locking the shoe support in operative position prior to the starting of the power operation of the machine, the construction shown comprising locking mechanism which is actuated or rendered operative by the rearward movement of the shoe support independently of the starting of the machine.

The above and other features of the invention, including novel means for adjustably varying the position of a shoe-supporting member, and various details of construction and combinations of parts, will now be more particularly described by reference to the accompanying drawing and pointed out in the claims.

The drawing shows in side elevation a heel end lasting machine of the type shown in the earlier application, with the present invention embodied therein. The machine com-

prises a base 2 on which is mounted a head 4 which supports a heel band 6 and heel-lasting wipers 8. The wipers are operated to lay the heel end of the upper inwardly over the insole by power-driven mechanism, not shown in detail, to which movement is imparted by a cam shaft 10 through a clutch controlled by a starting treadle 12. The heel band 6 comprises a flexible member which wraps itself automatically about the heel end of the shoe to clamp and shape the upper to the heel end of the last as the shoe is moved rearwardly against the band.

Pivoted at 14 on the base 2 is a shoe support or jack comprising a standard 16 provided with an eye-bar 18 for supporting loosely the lower end of a rod 20 on which is mounted for vertical adjustment a tubular member 22. Mounted for vertical adjustment in the upper end of the member 22 is a bar 24 provided with a heel pin 26 to engage in the spindle 75 hole of a last and having ratchet teeth arranged to be engaged by a spring-pressed pawl 28 on the member 22 to hold the heel pin in adjusted position. Clamped to the member 22 is a toe rest standard 30, and pivotally mounted at 32 on this standard is a toe rest holder 34 provided with an upwardly extending shank portion 36 on which is slidably mounted a toe rest member 38. The member 38 carries a pin 40 which extends into a groove 85 in the shank 36 to prevent the member 38 from turning, and also carries a spring-pressed pawl 42 for engagement with ratchet teeth on the shank 36 to hold the toe rest member in adjusted position. The holder 34 carries a detent 44 for engagement with teeth 46 on the standard 30 to hold the toe rest in any position to which it may be adjusted lengthwise of the shoe. The heel pin and the toe rest may thus be adjusted upwardly or downwardly, each independently of the other, to position any style or size of shoe in correct relation to the wipers, and the toe rest may also be adjusted to accommodate it to different lengths of shoes.

The tubular member 22 extends upwardly between spaced ears 48 at the front of the upper end of the standard 16, and has secured thereon a collar 50 engaged on its front face by the inner end of a screw 52 which is threaded in a bracket secured to the ears 48 and is operated by a hand wheel 54. Adjustment of the screw 52 thus serves to impart to the mem-

100

105

ber 22 and the parts which are carried thereby rearward movement relatively to the standard 16, or to permit them to be swung forwardly by the action of a spring plunger 56 which is mounted in the collar 50 and engages a portion of the standard 16. As herein-after described, the standard 16, after being swung rearwardly to force the shoe against the heel band, is locked invariably in the same operative position, and the means described for adjusting the member 22 relatively to the standard accordingly serves to determine the lengthwise position of the shoe in operative relation to both the heel band and the wipers. 15 The shoe support is intended to be swung rearwardly by the operator before the machine is started, and the machine is provided with means which operates automatically in response to such rearward movement of the shoe support to lock the support in operative position. For this purpose there is mounted in bearings in the base 2 a rock shaft 58 upon which is secured a locking member or lever 60 having a hook-shaped front end to engage a roll 62 on the standard 16. At its rear end the lever 60 is provided with a tooth 64 arranged to be engaged by a latch member 66 on the lower end of a rod 68 to hold the lever initially in idle position with its hook-shaped end upraised, as illustrated in the drawing. The rod 68 is pivoted at its upper end to one arm of a bell-crank lever 70, and is connected to a spring 72 which tends to pull the rod upwardly and also to hold it forwardly in position for its latch 66 to engage the tooth 64. On the lower end of the latch 66 is a finger 74 in position to be engaged by the rear end of a rod 76 which is pivotally connected at its front end to the standard 16 and is arranged to slide through a bearing formed in a bracket member 78, the rod 76 having thereon a nut 80 for engaging the member 78 to limit the forward movement of the shoe support. When the shoe support is swung rearwardly by the operator, the rod 76 pushes the latch 66 out of engagement with the tooth 64 as soon as the roll 62 passes to the rear of the hook-shaped end of the lever 60, and the lever is thereupon swung into locking position 45 by a torsion spring 82 which encircles the rock shaft 58. To limit the swinging movement of the lever, there is provided an abutment 84 on the base 2 which is engaged by a pad 86 on the lever. 50 Near the end of the cycle the cam 88 thereafter imparts downward movement to the latch and thereby swings the lever 60 to its idle position to release the shoe support.

55 The bell-crank 70 is controlled by a cam 88 on the cam shaft 10, and in the course of the cycle of operations of the machine the cam permits the spring 72 to raise the rod 68 until its latch 66 again connects with the tooth 64. 60

60 Near the end of the cycle the cam thereafter imparts downward movement to the latch and thereby swings the lever 60 to its idle position to release the shoe support.

65 The means thus provided for locking the shoe support in operative position prior to the

starting of the machine has important advantages in the use of the machine to last tennis shoes, in the manufacture of which neither the upper nor the insole is fastened to the last, since it enables the operator to position the insole in proper relation to the last and to the heel end of the upper after the upper has been clamped to the last by the heel band. In the use of the machine the operator mounts the last with its upper upon the shoe support, and after positioning the heel end portion of the upper with its margin projecting the proper distance above the heel seat face of the last, and while holding the upper in proper position, swings the shoe support rearwardly to force the shoe against the heel band, which wraps itself about the heel end of the shoe by the pressure of the shoe against it and thus clamps the upper to the last. In response to such rearward movement of the shoe support the lever 60 is released and locks the support in operative position. The operator then places an insole upon the bottom of the last in proper lengthwise position determined by pressing it back against the up-standing margin of the heel end of the upper. While holding the insole in position, he then depresses the treadle and starts the machine. The lasting operations of the machine are then performed in the manner described in the copending application, after which the shoe support is released by the action of the cam 88, in the manner hereinbefore explained, to permit it to swing forwardly into position for the operator conveniently to remove the shoe.

Having described the invention, what I claim as new and desire to secure by Letters Patent of the United States is:—

1. In a shoe machine, the combination with power-driven means for operating on a shoe, of a shoe support mounted for movement to carry a shoe into position for the operation of said means, and locking means mounted independently of the shoe support and arranged to be actuated by said movement of the support substantially at the end of such movement to lock the support with the shoe in said position prior to the starting of the machine.

2. In a shoe machine, the combination with means for operating on a shoe, of a shoe support mounted for movement to carry a shoe into position for the operation of said means, and a spring-operated locking device arranged to be tripped by said movement of the shoe support to lock the support with the shoe in said position.

3. In a shoe machine, the combination with means for operating on a shoe, of a shoe support mounted for movement to carry a shoe into position for the operation of said means, a member for locking the shoe support with the shoe in said position, a latch for holding said member normally in idle position, and means for operating said latch by said move-

ment of the shoe support to cause it to release the locking member.

4. In a shoe machine, the combination with power-driven means for operating on a shoe, and a member for starting said power-driven means in operation, of a shoe support movable manually to carry a shoe into position for the operation of said means, and a device arranged to be tripped by such movement of the 10 shoe support to lock the support with the shoe in said position prior to the operation of said starting member.

5. In a shoe machine, the combination with power-drive means for operating on a shoe, 15 of a shoe support mounted for movement to carry a shoe into position for the operation of said means, a device automatically operative in response to said movement of the shoe support and independently of the starting of 20 the machine to lock the support with the shoe in said position, and power-operated means for subsequently operating said device to unlock the support.

6. In a machine of the class described, the 25 combination with power-driven means for operating on a shoe, of a shoe support mounted for swinging movement rearwardly to carry a shoe into position for the operation of said means, and a device arranged to act 30 automatically in response to said rearward movement of the shoe support to lock the support against return forward movement before the machine is started.

7. In a machine of the class described, the 35 combination with power-operated end-lasting mechanism, of a shoe support mounted for movement to carry a shoe into position for the operation of said mechanism, and a device automatically operative in response to said 40 movement of the shoe support and independently of the starting of the machine to lock the support with the shoe in said position for the inspection of the operator prior to the beginning of the lasting operation.

45 8. In a machine of the class described, the combination with means for lasting the heel end of a shoe comprising a heel-embracing band and power-operated wipers, of a shoe support mounted for movement to carry a last 50 with its upper rearwardly against said band to position it for the operation of the wipers, and a device automatically operative in response to said movement of the shoe support to lock the support with the last and 55 upper in said position independently of the starting of the machine to enable the operator to position an insole upon the bottom of the last while the upper is clamped by the band about the heel end of the last.

9. In a shoe machine, the combination with 60 means for operating on a shoe, of a shoe support mounted for positioning movement to carry a shoe into position for the operation of said means, said shoe support comprising a standard and a shoe-supporting member 65 mounted on said standard for adjusting movement relatively to the standard in the direction of said positioning movement of the support, means for imparting adjusting movement to said member, and spring means 70 against the resistance of which said adjusting movement is effected.

10. In a shoe machine, the combination with 75 means for operating on a shoe, of a shoe support movable rearwardly to carry a shoe into position for the operation of said means, said shoe support comprising a standard and a shoe-supporting member mounted on said standard for adjusting movement relatively to the standard in directions parallel to the 80 direction of the positioning movement of the support, a screw arranged to bear on the front of said member for moving it rearwardly, and a spring at the rear of said member for holding it forwardly against said screw. 85

11. In a shoe machine, the combination with 90 means for operating on a shoe, of a shoe support mounted for positioning movement to carry a shoe into position for the operation of said means, said shoe support comprising 95 a standard having a part thereon arranged to co-operate with a locking member to lock said standard invariably in the same position in operating on different shoes, a shoe-supporting member mounted on said standard for adjusting movement relatively to the standard in the direction of the positioning movement of the support, and means for imparting said adjusting movement to said member. 100

12. In a shoe machine, the combination with 105 means for operating on a shoe, of a shoe support mounted for movement to carry a shoe into position for the operation of said means, said shoe support comprising a standard mounted for rearward swinging movement and having a part thereon arranged to co-operate with a locking member to lock said standard invariably in the same position in operating on different shoes, a shoe-supporting member mounted on said standard for rearward or forward swinging movement relatively to the standard, a device for adjusting said member rearwardly, and spring means for swinging said member forwardly. 110

In testimony whereof I have signed my 115 name to this specification.

BERNHARDT JORGENSEN.
